AIR-SWEPT PULVERIZER HAVING INTERNAL FLOW AREA ADJUSTING MEANS

George B. Ebersole, Akron, Ohio, assignor to The Babcock & Wilcox Company, Rockleigh, N. J., a corporation of New Jersey

Application August 14, 1943, Serial No. 498,632

13 Claims. (Cl. 241—53)

1

The invention herein disclosed relates to a pulverizer having relatively movable grinding elements arranged to reduce various kinds of solid materials such as coal, limestone, ores, and the like, to a fine state of pulverization, the finely divided solid products being transported through and from the pulverizer by means of a current of carrier air whereby the resulting pulverizer output is a fluent mixture comprising pulverulent material suspended in the stream of carrier air; the term "air" to be construed broadly as including air per se and other suitable gaseous carrier media, whether used singly or in combination. In such a pulverizer, herein identified as an air-swept pulverizer, the carrier air may be introduced under pressure at a location remote from the pulverizer outlet, or may be caused to pass through the pulverizer under an induced draft condition maintained at the pulverizer outlet.

The invention is especially directed to an air-swept pulverizer having a grinding zone in a lower portion thereof generally defined by grinding elements comprising a plurality of grinding balls arranged in a circular row and cooperating with the grinding surfaces of rings above and below, the carrier air being caused to flow upwardly through said zone in opposition to the downward feed of raw unground material, and being admitted to said zone through a relatively narrow annular throat to provide a sufficiently high velocity to effect separation of finely ground particles from coarser particles, and to promptly remove such finely divided products from the grinding zone for continuous discharge from the pulverizer.

When such a pulverizer is operated at varying capacities, it is customary to vary the rate of air flow through the pulverizer in appropriate relation to the weight of pulverized material being discharged per unit of time; in general, a greater quantity of air being supplied for higher output capacities than for lower capacities. When coal for example is being pulverized, for use in burners having a direct connection with the pulverizer, the rate of air flow is preferably maintained sufficiently high at various pulverizer outputs to provide proper burner velocities and to prevent coal from accumulating in the pulverizer faster than it is carried out by the air; on the other hand, too high a rate of air flow for a given output will sweep the pulverizer of coal too rapidly with a resulting depreciation in coal fineness.

It is evident that with a fixed mechanical arrangement of parts within the pulverizer, resulting for example in a fixed throat area, the range

of output capacity is limited at least in part by the characteristics of air flow through the throat passage and the amount of pressure drop involved at one or the other of the extreme load conditions.

- 5 For example, a pulverizer may be capable of operating efficiently at maximum load with the desired velocity of air flow through and adjacent the grinding zone, and with a normal pressure drop value, whereas at minimum rating due to 10 the decrease in air flow, the velocity of air flow into and through the grinding zone may become less than that desired for satisfactory separation of the fine and coarse particles, and the continuous removal of the fines from the grinding zone.
- 15 If the internal mechanical relation of parts is fixed for a suitable velocity of air flow through the throat and grinding zone at minimum rating, the pressure drop through the pulverizer may become excessive at maximum rating, resulting 20 in coarseness of the product and abnormal increase in fan power required to maintain the required current of carrier air.

An object of the subject invention is therefore 25 to provide an air-swept pulverizer having internal flow area adjusting means whereby the pulverizer may be operated at varying outputs while maintaining a minimum variation in air flow characteristics through and adjacent the grinding zone.

- 30 An additional object is to provide an internal mechanical arrangement of parts within an air-swept pulverizer whereby the velocity rate of air admission to the grinding zone can be maintained within a predetermined range irrespective of variations in the quantity of air supplied.

Another object is to provide an air-swept pulverizer wherein the mechanical relation of parts within the pulverizer may be adjusted in accordance with varying pulverizer output capacities.

- 40 Further objects include adjustment of pulverizer throat area simultaneously throughout its circumference, and alternatively, selective, localized adjustment at predetermined circumferential locations.

45 These and other objects and features of the invention will be readily understood from the description to follow, particularly when read in conjunction with the accompanying drawings, in which:

50 Fig. 1 is a sectional elevation of a pulverizer embodying elements of my invention;

Fig. 2 is an enlarged fragment of Fig. 1 showing certain parts in a different position of adjustment;

Fig. 3 is a sectional plan of Fig. 1 taken along line 3—3;

Fig. 4 is an enlargement of the operating mechanism seen in Fig. 3;

Fig. 5 is a sectional elevation showing a modification;

Fig. 6 is a partial sectional plan of Fig. 5, taken along line 6—6;

Figs. 7 and 8 are fragmentary plan and side views illustrating modified details of construction; and

Fig. 9 is a fragmentary sectional elevation showing a further modified detail.

In detail, and referring particularly to Figs. 1 to 4, inclusive, the pulverizer shown is of a known ball mill type having a casing 10 substantially cylindrical in form in which a circular series of grinding balls 12 operates between upper and lower grinding rings 14 and 16, respectively; the lower ring 16 being held stationary and the upper ring 14 being rotated about a vertical axis by means of the drive ring 18 driven through a spider 20, yoke 22, main shaft 24 and pinion shaft 26 from a convenient source of motive power, not shown. Pressure between the grinding balls and rings is resiliently maintained through springs 28 acting between the drive ring 18 and spider arm 30, and the pressure adjusted by means of longitudinally adjustable spring bolts 32. The material to be pulverized, otherwise known as raw material, is fed to the pulverizer or mill through an inlet 34 at a level preferably above the grinding zone generally defined by the grinding balls 12 together with the cooperating grinding rings 14 and 16.

A support ring, or base plate 36, at the bottom of the mill is provided with a series of radial ports 38 at intervals throughout its circumference through which air or other gaseous medium is introduced to the grinding zone for transporting finely divided particles of the raw material from the mill after pulverization, the ground material or fines being carried upwardly within the mill casing 10 and being discharged through one or more outlets 40 in the top wall of the casing. Thus, the resulting pulverizer output is essentially a fluent mixture comprising finely divided solids suspended in the gaseous carrier medium which for the purpose of this application is termed "air" regardless of its specific identity. The carrier air enters the mill through an air inlet 42 leading to an air compartment 44 adjacent the periphery of the ported support ring 36 and separated from the upper mill space 46 by the conical wall 48 extending upwardly from the rim of the support ring 36 to the cylindrical wall of the casing 10.

An extension piece 50 is secured to the spider 20 for rotation therewith, such a piece to be referred to herein as the spider extension, and being of hollow conical formation toward its base to provide a circumferential outer rim surface 52 annularly spaced from the inner periphery of the lower grinding ring 16 to form a relatively narrow annular throat passage 54 for admission of the carrier air to the grinding zone from below. The required width of the throat passage is determined from known characteristics of the mill under consideration, and may conveniently be made the same width for variable capacity operation, in accordance with the present invention, as is normally required for efficient operation at the maximum capacity rating.

In providing for operation of the pulverizer at widely different capacities, since it is desirable

to maintain a suitable minimum air flow velocity through the pulverizer throat, for a given output capacity, and a minimum variation in pressure drop for a given range of capacities, it is proposed to employ a suitable valving means whereby the effective area of the throat passage may be adjusted between maximum and minimum limits; for maximum load the effective throat area being maximum and substantially equal to the total available throat area, whereas for minimum load, the effective throat area is adjusted to its minimum value representing a fractional part of the total available throat area.

With the throat valve in any one position of adjustment, maximum, minimum, or intermediate, it will be understood that the pulverizer may be operated satisfactorily over a limited range of output capacities, but with a shift of the valve from one position to another, the individual range values are combined to provide a considerably extended total operating range, the successive range values preferably overlapping to an extent insuring a gradual transition from one range to another. In such an arrangement, the air flow velocity through the throat may be desirably maintained at the same minimum value for the low capacity limits of successive ranges.

The valving mechanism is preferably to be arranged so that the desired adjustments of throat area may be made entirely from the exterior of the pulverizer, a feature which is particularly advantageous when temporary load changes are to be accommodated as, for example, when a unit is to be put on reduced load over the weekend and then restored to normal operating load, with little or no stoppage and without structural alterations.

In one form, as illustrated in Figs. 1—4, the valving means may comprise an annular member or throat ring 56 arranged concentrically with the pulverizer throat 54 and adjustable axially in relation thereto. As seen in cross section, the ring 56 may be of substantially uniform thickness throughout, the inner and outer surface portions adjacent the top edge 58 being substantially parallel to the throat axis, and corresponding surface portions adjacent the bottom edge 60 flaring outwardly toward the air ports 38 in the support ring 36. Fig. 1 shows the ring 56 in the fully retracted position for maximum capacity, while Fig. 2 shows the ring 56 in the fully advanced position for minimum capacity where the top edge 58 of the ring is for all practical purposes level with the bottom edge 62 of the spider extension 50, thereby blocking off a portion of the throat passage 54 and affording an effective throat area less than the maximum available throat area by an amount substantially equal to the transverse cross section of the ring in the plane of its top edge 58. The diameter of the valve ring 56 at its top edge is preferably so selected that the outer annular throat space 64 constitutes the major proportion of the effective throat area, leaving a relatively small inner annular space 66 between the ring 56 and spider extension surface 52, principally for mechanical clearance purposes. A band of metal 68 may be welded or otherwise added to the rim of the spider extension to provide ample thickness to allow for machining to a true predetermined diameter.

The annular valve ring 56 is supported by spokes 70 extending radially and downwardly from a circular support plate 72, a tubular post 74 being mounted axially of the plate and secured thereto as by welding 76, to receive an

axially movable actuating rod 78 arranged for integral assembly therewith, the rod 78 having a collar 80 toward its lower end against which the lower end of the tubular post 74 abuts, while the upper end of the rod is threaded for a nut 82 by which the valve ring assembly and actuating rod may be removably maintained in fixed relation.

An inverted conically formed cup-like member 84 is secured to the pulverizer base plate 36 to form a support and guide for the valve ring assembly, and to provide a housing or cover for the valve ring operating mechanism to be described, the top wall or cover plate 86 being made removable to permit access to such mechanism.

The cover plate 86 of the housing 84 is recessed as at 88 to accommodate the enlargement on the post 74 caused by the attaching material 76, to allow the support plate 72 of the valve ring assembly to rest on the cover plate 86 of the housing when the valve ring 56 is in its fully retracted and lowermost position as seen in Fig. 1; in this position, the projections 90 on the spokes 70 resting against the conical outside wall 92 of the housing. The cover plate 86 also provides a sleeve portion 94 forming a guide for the post member 74 whereby axial alignment of the valve ring 56 with the throat 54 is maintained at all positions to which the valve ring may be adjusted.

The operating mechanism for moving the valve ring 56 includes an operating shaft 96 lying adjacent the floor of the mill and extending horizontally from outside of the mill casing 10, through one of the air ports 38, through the side wall 92 of the housing 84, to a point laterally adjacent the central axis of the pulverizer. A tube 98 suitably secured to adjacent fixed parts of the pulverizer serves as a bearing sleeve and cover for the operating shaft 96. A crank arm 100 formed with a clevis 102 is suitably secured to the operating shaft 96 at its inner end, where a connection through link 104 is made to a clevis 106 formed at the lower end of the actuating rod 78. The operating shaft 96 may be rotated by means of lever 108 secured to the shaft 96 exteriorly of the casing 10, the angular displacement being limited by the arcuate lever slot 110 in cooperation with a stud or bolt 112 secured to a stationary part of the mill structure, the bolt 112 also serving as a clamping means for holding the shaft 96 and thereby the throat ring 56 in the desired adjusted position.

In the arrangement shown, angular movement of the shaft 96 is limited to approximately 55° which is sufficient to rotate the crank arm 100 from a position where the pin connection 114 is in a horizontal plane with the axis of the shaft 96 to a position where the pin connection 114 is in a vertical plane with the central axis of the adjustable throat ring 56. Clockwise rotation of the lever 108 through the angle 55° as described will thus cause the throat ring 56 to be moved upwardly from its lowermost maximum capacity position to its uppermost minimum capacity position, in either of which positions, or in any intermediate position, the throat ring may be secured against accidental displacement by means of the clamping bolt 112.

In the modification according to Figs. 5 and 6, an air-swept pulverizer of the same general type as in Figs. 1 and 2 is shown, wherein a series of grinding balls 12 operates between a rotatable upper grinding ring 14 and a stationary lower grinding ring 16, and carrier air from

the compartment 44 is directed radially through air ports 38 in the base plate or support ring 36a and upwardly through the annular throat passage 54 formed between the inner periphery of the stationary lower grinding ring 16 and the rotatable spider extension 50a. In this form, adjustment of effective throat area is accomplished by means of a ring 120 positioned below the pulverizer throat 54 adjacent the bottom surface 122 of the lower grinding ring 16, the ring 120 being formed as a segmental structure so that its diameter may be varied between predetermined limits to effect a corresponding variation in the effective throat area.

The ring 120 as shown is formed of arcuate segments 124 shaped as at 126 on the side facing the throat to approximate the contour of the opposing outer wall surface 128 of the spider extension 50a whose bottom edge 130 is positioned opposite the air ports 38 at a level slightly below the segmental ring 120. The ring segments 124 are individually movable radially of the throat passage 54 and are resiliently held in contact with the grinding ring surface 122 by means of spring clips 132 circumferentially spaced and suitably secured to the base plate 36a as by bolts 134, each segment being symmetrically mounted on an actuating rod 136 extending radially through a bore 138 in the solid metal of the base plate 36a intermediate the air ports 38. Each rod 136 terminates exteriorly of the casing 10 in a threaded end 140 to receive an adjusting nut 142 whereby the desired radial position of a segment 124 may be maintained; the segment tending to be moved inwardly due to the biasing effect of the spring 144 acting in compression between spring seat 146 fixed to the rod 136 and spring seat bushing 148 fixed to the mill casing 10, and the tendency for such inward movement being opposed by the adjusting nut 142.

The ring segments 124 as shown are of substantially equal arcuate lengths and at their ends 150 are formed parallel to their respective axes of radial movement, the arcuate lengths of individual segments being such that when the ring 120 is contracted and all segments are moved to their normal innermost position, as indicated by the dot-and-dash circumference 152 in Fig. 6, the inner surfaces 126 collectively provide a substantially continuous surface of revolution. When the ring is expanded and all segments are moved to their extreme outermost position, as indicated by the full line showing in Fig. 6, the ends 150 of adjacent segments are separated by a small tapering gap 154 constituting a relatively minor proportion of the total effective throat area and since such gaps are distributed about the entire circumference their presence is no detriment to successful operation.

Since the ring segments 124 are individually movable, the arrangement of Figs. 5 and 6 also enables localized adjustments of throat area to be made at predetermined circumferential locations, thereby compensating for the unequal distribution of air flow that might occur because of the single air inlet 42 at the side of the casing requiring the air to travel different distances to enter different ports 38. It is possible that irregularities in the throat surfaces or in their spaced relation, incident to machining or assembling, might also make such localized adjustment desirable.

The arrangement of Figs. 5 and 6 may also be found advantageous in that for all positions of

the ring 120, the effective throat area lies between a rotating and a non-rotating wall, thereby lessening the tendency for particles of unpulverized material to become lodged in the throat gap and possibly interfere with the intended air distribution. This is in contrast with the arrangement of Figs. 1-4 where with the ring 56 in an elevated position for minimum effective throat area, the resulting throat gap lies between opposing non-rotating walls.

Figs. 7 and 8 illustrate a modification providing for simultaneous actuation of the ring segments 124 which in these views are shown in an intermediate position of adjustment. In this form, each actuating rod 136a is suitably supported and guided in the bore 138, and at its outer end by the casing 10, and at an intermediate location carries a downwardly extending pin 156 adapted to engage a cam slot 158 in the horizontally disposed and angularly adjustable cam ring 160. The cam slots 158 are arranged at a suitable inclination to the axes of the respective actuating rods 136a so that for a predetermined angular adjustment of the cam ring 160 all segments 124 are simultaneously moved radially to the extent desired, thereby effecting substantially uniform adjustment of throat flow area throughout the entire circumference. The cam ring may be supported on bosses 162 at circumferentially spaced locations to minimize friction and to provide a clearance space between the cam ring and the mill floor so that the follower pins 156 may extend through the cam slots 158 for the full ring thickness, and furthermore so that any accumulation of dust at the bottom of the mill will not interfere with cooperation of the pins and ring. A bar or stud 164 is suitably secured to the cam ring 160 at its outer periphery, as by threads 166, and extends outwardly through an elongated slot 168 in the mill casing 10 thereby enabling the position of the cam ring to be adjusted from the exterior, the washer 170 and nut 172 enabling the cam ring to be clamped in the desired position of adjustment within limits determined either by the length of cam slot 158 or casing slot 168.

Fig. 9 illustrates a modified adjustment detail providing for positive actuation of individual rods 136 in opposite directions, and adapted for use in place of the spring arrangement shown in Fig. 5. A flanged bushing 174 rotatably mounted on the mill casing 10 is fitted with a nut 176, for example, secured thereto as by a weld 178 to prevent longitudinal displacement. The bushing is interiorly threaded for cooperation with the threaded end 140 of the actuating rod 136, whereby upon angular adjustment of the bushing by means of the nut 176 or other suitable form of adjusting means, the actuating rod 136 is longitudinally advanced or retracted to effect a corresponding radial adjustment of the associated ring segment 124. A pin 180 through the rod 136 may be employed as a stop to limit inward movement of a segment 124 to prevent inadvertent engagement of any segment with the rotatable spider extension 50a, such a stop means being adapted for similar application to the rod-adjusting detail of Fig. 5.

The invention as herein disclosed in accordance with the provisions of the statutes will be understood by persons skilled in the art to be applicable in arrangements other than those specifically described, and to include features which may be used to advantage without a correspond-

ing use of other features, within the scope of the appended claims.

I claim:

1. In a pulverizer comprising a casing having an outlet in its upper portion for pulverized material suspended in carrier air, upper and lower grinding rings in a lower portion of the space enclosed by said casing, a circular series of grinding balls intermediate said rings and cooperating therewith to define a pulverizing zone, means axially and radially fixed in relation to said lower ring and forming therewith an annular throat of constant available flow area adjacent the inner circumference of said lower ring for upward flow of carrier air into said zone, adjustable valving means independent of and movable relative to said means forming said throat for rendering effective different proportions of said available throat area, and means for moving said adjustable means to a position rendering effective the total available flow area of said throat.

2. In a pulverizer comprising a casing having an outlet in its upper portion for pulverized material suspended in carrier air, upper and lower grinding rings coaxially arranged in a lower portion of the space enclosed by said casing, a circular series of grinding balls intermediate said rings and cooperating therewith to define a pulverizing zone, means for rotating one of said rings and thereby causing said balls to roll relative to both of said rings, means for feeding raw material to said zone adjacent the outer periphery thereof, means rotatable about the axis of said rings and axially fixed in relation to the lower of said rings for defining an annular throat of constant available flow area adjacent the inner circumference of said lower ring for upward flow of carrier air into said pulverizing zone, adjustable valving means independent of and movable relative to said means defining said throat for rendering effective different proportions of said available throat area, and means operable from the exterior of said casing for moving said adjustable means to a position clear of said throat for rendering effective said constant available flow area of said throat.

3. In a pulverizer comprising a casing having an outlet in its upper portion for pulverized material suspended in a current of carrier air, vertically spaced grinding rings in a lower portion of said casing including a rotatable upper ring and a non-rotatable lower ring, a circular row of grinding balls positioned intermediate said rings and cooperating therewith to define a grinding zone of said pulverizer, driving means in an upper portion of said casing for rotating said upper grinding ring and thereby causing said balls to roll relative to both of said rings, said driving means having a downwardly directed extension providing an outer surface of revolution inwardly spaced from the inner circumference of said lower ring for defining an annular throat therebetween for upwardly flowing carrier air, valving means movable relative to said extension and operable at a level below said throat for varying the effective flow area of said throat, and means for supporting and actuating said valving means comprising an axially disposed member extending upwardly within said extension.

4. In a pulverizer comprising a casing having an outlet in its upper portion for pulverized material suspended in carrier air, upper and lower grinding rings in a lower portion of the space

enclosed by said casing, a circular series of grinding balls intermediate said rings and cooperating therewith to define a pulverizing zone, means for feeding raw material to said zone adjacent the outer periphery thereof, a stationary support for and below the lower of said rings for maintaining said lower ring in predetermined axial position, means axially fixed in relation to said lower ring and forming an annular throat of constant available flow area adjacent the inner circumference of said lower ring for upward flow of carrier air into said zone, valving means independent of and movable relative to said means forming said throat for adjusting the effective flow area of said throat substantially throughout its circumference, said flow area adjusting means being movable to a position clear of said throat for rendering effective the total available flow area of said throat, means for controlling the movement of said movable means from a location exteriorly of said casing, said last named means comprising operating means extending laterally of and through said stationary support, and stop means for limiting throat area reducing movement of said valving means.

5. In a pulverizer comprising a casing having an outlet in its upper portion for pulverized material suspended in air, a circular row of grinding balls in a lower portion of said casing, upper and lower grinding rings cooperating with said grinding balls to define a grinding zone for raw material fed to said zone from the upper side thereof adjacent the outer periphery of said upper ring, a drive shaft coaxial with said rings and said row of balls, power transmitting means connected to said drive shaft for rotating said upper ring relative to said lower ring thereby causing said balls to roll relative to both of said rings, said power transmitting means having a downwardly directed tubular extension axially fixed in relation to said lower ring and flaring outwardly adjacent its bottom edge for defining with the inner circumference of said lower ring an annular throat for carrier air, means for causing an upward flow of carrier air through said throat into and through said grinding zone, and valving means annularly arranged and operable below the entrance to said throat and movable axially of said throat relative to said extension for adjusting the extent of throat area effective for said upward flow of carrier air, said last named means being movable from an upper position adjacent said throat to a lower and more remote position clear of said throat for rendering effective the maximum available flow area of said throat.

6. In a pulverizer comprising a casing having an outlet in its upper portion for pulverized material suspended in carrier air, upper and lower grinding rings coaxially arranged in a lower portion of the space enclosed by said casing, a circular series of grinding balls intermediate said rings and cooperating therewith to define a pulverizing zone, driving means rotatable about the axis of said rings for rotating said upper ring and thereby causing said balls to roll relative to both of said rings, means rotatable with said driving means extending downwardly through said pulverizing zone to form with the inner periphery of one of said rings an annular throat of constant area for upward flow of carrier air into said zone, means forming a circular series of ports for directing carrier air inwardly to a space below said throat, and annularly arranged valving means reciprocable axi-

ally of said throat relative to said rotatable means for varying the effective flow area of said throat, said reciprocable means being movable to a position clear of said throat for rendering effective the total flow area available between the opposing walls of said throat, said reciprocable means being formed as a circular band of gradually increasing diameter toward its lower edge to serve as a guide for air flowing from said ports to said throat.

7. In a pulverizer comprising a casing having an outlet in its upper portion for pulverized material suspended in carrier air, upper and lower grinding rings in a lower portion of the space enclosed by said casing, a circular series of grinding balls intermediate said rings and cooperating therewith to define a pulverizing zone, means axially and radially fixed in relation to the lower of said rings and forming therewith an annular throat of constant available flow area adjacent the inner circumference of said lower ring for upward flow of carrier air into said zone, and independent adjustable valving means movable transversely of said throat for rendering effective different proportions of said available throat area, said valving means comprising a series of circumferentially distributed elements each in slidable engagement with an under surface associated with said lower ring.

15 8. In a pulverizer comprising a casing having an outlet in its upper portion for pulverized material suspended in carrier air, upper and lower grinding rings in a lower portion of the space enclosed by said casing, a circular series of grinding balls intermediate said rings and cooperating therewith to define a pulverizing zone, means axially and radially fixed in relation to the lower of said rings and forming therewith an annular throat of constant available area adjacent a marginal circumference of said lower ring for upward flow of carrier air into said zone, and a ring structure arranged coaxially of said throat and formed of segmental portions independently movable transversely thereof for annularly adjusting the effective flow area of said throat.

9. In a pulverizer comprising a vertically disposed substantially cylindrical casing having an outlet in its upper portion for pulverized material suspended in carrier air, upper and lower grinding rings in a lower portion of the space enclosed by said casing, a circular series of grinding balls intermediate said rings and cooperating therewith to define a pulverizing zone, means for rotating one of said rings and thereby causing said balls to roll relative to both of said rings, means rotatable with said rotated ring and extending downwardly through said pulverizing zone to form an annular throat of constant area for upward flow of carrier air into said zone, an annular support adjacent the inner circumference of the lower of said rings for said lower ring below said ring and annularly spaced from said casing, said support having a series of ports therein distributed throughout its circumference for directing carrier air inwardly to a space below said throat, annular wall means extending from said support to said casing for defining an annular air compartment open throughout its inner circumference to the inlet ends of said ports, inlet means for admitting carrier air to said compartment at a location circumferentially removed from some of said ports a greater distance than from others, and annularly arranged valving means movable relative to said throat for selectively varying the effective flow area

11

dimensions of said throat in different amounts at different circumferential locations.

10. In a pulverizer comprising a casing having an outlet in its upper portion for pulverized material suspended in carrier air, upper and lower grinding rings in a lower portion of the space enclosed by said casing, a circular series of grinding balls intermediate said rings and cooperating therewith to define a pulverizing zone, means forming an annular throat of constant available area adjacent a marginal circumference of said lower ring for upward flow of carrier air into said zone, a segmental ring arranged coaxially of said throat and formed of portions adjustable radially in relation thereto for varying the effective flow area dimensions of said throat substantially throughout its circumference, and means for simultaneously adjusting a plurality of said segmental ring portions.

11. In an air swept pulverizer adapted for operation over different ranges of output capacities, wherein air is caused to pass through the grinding zone of said pulverizer in quantities proportionate to pulverizer output capacities throughout each range, said pulverizing zone including a series of grinding elements operable in a circle about a central axis to provide a pulverizing zone of generally annular formation, means forming an annular throat of constant available flow area for admitting said air to said zone marginally of said series of grinding elements in an annular stream of maximum cross section for capacities in a high capacity range, and means for admitting said air to said zone in an annular stream of minimum cross section for capacities in a lower capacity range, said last named means comprising annularly arranged valving means independent of and adjustable relative to the opposing walls of said throat for rendering varying proportions of said constant available flow area effective, said adjustable means being movable into an advanced position adjacent said throat for providing said minimum cross section of stream and into a retracted position clear of said throat for providing said stream of maximum cross section.

12. In an air swept pulverizer adapted for operation over successive ranges of output capacities, wherein the quantity rate of air flow through the grinding zone of said pulverizer is increased with increasing capacities throughout each range, means forming said grinding zone comprising a ring member having an annular grinding sur-

face together with a circular row of grinding elements rollable in relation to said surface, means arranged concentrically with respect to said ring member and annularly spaced from a periphery thereof to form an annular throat therebetween of fixed available flow area, means for directing carrier air upwardly through said throat from a pulverizer space below said ring member, valving means independent of and adjustable within said space relative to the opposing walls of said throat substantially throughout the circumference of said throat for varying the extent of said throat area effective for different ranges, means for adjusting said last named means from a position rendering a minimum amount of said fixed available throat area effective to a position rendering the total amount of said throat area effective, means for maintaining the adjustment of effective flow area constant for any given component range, and stop means for limiting throat area reducing movement of said valving means.

13. In a pulverizer comprising a casing having an outlet in its upper portion for pulverized material suspended in carrier air, upper and lower grinding rings in a lower portion of the space enclosed by said casing, a circular series of grinding balls intermediate said rings and cooperating therewith to define a pulverizing zone, means axially and radially fixed in relation to the lower of said rings and forming therewith an annular throat of constant available area adjacent a marginal circumference of said lower ring for upward flow of carrier air into said zone, and a substantially continuous ring structure arranged coaxially of said throat and formed of portions movable transversely thereof for annularly adjusting the effective flow area of said throat.

Certificate of Correction

June 21, 1949

Patent No. 2,473,514

GEORGE B. EBERSOLE

It is hereby certified that errors appear in the printed specification of the above numbered patent requiring correction as follows:

Column 10, lines 60 and 61, strike out "adjacent the inner circumference of the lower of said rings" and insert the same in line 59, before the word "for"; and that the said Letters Patent should be read with these corrections therein that the same may conform to the record of the case in the Patent Office.

Signed and sealed this 16th day of May, A. D. 1950.

[SEAL]

THOMAS F. MURPHY,
Assistant Commissioner of Patents.
